UNITED STATES PATENT OFFICE

168,723

COMBINED CLOCK AND RADIO CABINET

Samuel E. Adler, Chicago, Ill.

Application June 11, 1952, Serial No. 20,131

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Combined Clock and Radio Cabinet, of which the following is a specification, reference being had to the accompanying drawings, forming a part hereof.

Fig. 1 is a front elevational view of a combined clock and radio cabinet, showing my new design;

Fig. 2 is a top plan view thereof;

Fig. 3 is an elevational view of the right side thereof;

Fig. 4 is an elevational view of the left side thereof; and

Fig. 5 is a fragmentary sectional view, the origin of which is indicated by line 5—5 of Fig. 1.

The dominant features of my new design reside in the portions shown by full lines of the drawings.

I claim:

The ornamental design for a combined clock and radio cabinet, as shown and described.

SAMUEL E. ADLER.
